UNITED STATES PATENT OFFICE.

JAMES A. BONSACK AND HUGO BILGRAM, OF PHILADELPHIA, PENNSYLVANIA, ASSIGNORS TO THE BONSACK MACHINE COMPANY, OF SALEM, VIRGINIA.

CIGARETTE MACHINERY.

SPECIFICATION forming part of Letters Patent No. 594,375, dated November 30, 1897.

Application filed January 7, 1897. Serial No. 618,422. (No model.)

To all whom it may concern:

Be it known that we, JAMES A. BONSACK and HUGO BILGRAM, citizens of the United States, residing in the city and county of Philadelphia, in the State of Pennsylvania, have invented certain new and useful Improvements in Cigarette Machinery, of which the following is a true and exact description, reference being had to the accompanying drawings, which form a part thereof.

The present invention relates generally to mechanism for forming tobacco fillers for cigarettes, in which the tobacco in regulated or measured quantity is fed or showered upon a receiving-surface, which is divided into equal compartments, in such manner that each compartment shall receive the desired quantity or parcel of tobacco for a cigarette-filler. The parcels of tobacco thus formed are successively discharged from the receiving-compartments and are delivered to mechanism by which they are compressed into the proper form of cigarette-filters, this compressing mechanism being driven or operated in unison with the mechanism by which the parcels are delivered thereto, whereby the movements of each of these mechanisms are so related to each other that each parcel of tobacco will be delivered at the proper time to be acted upon by the compressing mechanism; and the invention consists in the various novel features of construction and combination of parts, which will be more particularly described in the following specification and pointed out in the claims.

For a full understanding of the invention a detailed description of a machine of the preferred form embodying the same will now be given in connection with the accompanying drawings, forming a part of this specification, in which—

Figure 1 is a front elevation of a part of a cigarette-machine embodying our invention, certain parts being shown in section. Fig. 2 is a plan view of the parcel-forming apron or belt divided into compartments, as seen from horizontal section along line 2 2 of Fig. 1. Fig. 3 is an end elevation as seen from the left hand of Fig. 1, the filler-compressing mechanism being omitted. Fig. 4 is a cross-section along line 4 4 of Fig. 1, looking to-

ward the right. Fig. 5 is an end elevation as seen from the right hand of Fig. 1. Fig. 6 is an enlarged end view of the parcel-discharging mechanism, certain parts being broken away and others shown in section. Fig. 7 is a vertical section along line 7 7 of Fig. 6 to show the construction and operation of the parcel-discharging mechanism, certain parts being omitted and certain parts being shown in dotted lines on either side of the section-lines. Fig. 8 is a side elevation as seen from the left hand of Fig. 6. Figs. 9 and 10 are detail views of the compartment-apron. Fig. 11 is a sectional view of a modification of certain parts of the mechanism shown in Fig. 4 for delivering the tobacco to the compartment-apron, the section being taken along the same line as in Fig. 4. Fig. 12 is a view of a conical or tapered cigarette-filler, and Fig. 13 is a view of a cigarette-filler of uniform diameter throughout its length.

Referring to the drawings, A is a hopper supported upon the frame of the machine and forming the upper part thereof and adapted to receive tobacco to be operated upon to form cigarette-filters.

B and C are cylinders or rolls constructed and arranged to rotate in the hopper, the cylinder B being designated the "feed-cylinder" and the cylinder C the "filling-cylinder." These cylinders are arranged so that their adjoining surfaces will be quite near each other, and they rotate upon their axes in the same direction, which causes their contiguous surfaces to move in opposite directions. The surface of the feed-cylinder B is provided with rows of teeth, which preferably incline in the direction of the rotation of the cylinder, which is indicated by the arrow on Fig. 4. The surface of the filling-cylinder C is also preferably provided with short teeth or other roughened surface, the teeth being inclined in a direction opposite to the rotation of the cylinder. The feed-cylinder B is connected with the driving mechanism, so as to rotate continuously, but the filling-cylinder is arranged to rotate intermittently, preferably having a peripheral speed, when moving, greater than that of the feed-cylinder, for the purpose hereinafter set forth. There is also shown in the

- drawings a brush-roll D, arranged to operate in connection with the cylinder C to remove therefrom any particles or fibers of tobacco which may be retained thereon. A stripper 5 roll E, provided with teeth arranged to operate between the teeth of the feed-cylinder, is arranged to rotate in connection therewith. The location and relative arrangement of these cylinders or rolls is clearly shown in 10 Fig. 4, in which the cylinder B occupies the bottom part of the hopper, the lower part of its periphery being in close proximity to the wall of the hopper and its upper part being in position to receive and support the mass 15 of tobacco as it is placed in the hopper. The filling-cylinder C is arranged above and somewhat in front of the cylinder B and preferably in such relation thereto that the teeth of their contiguous surfaces are nearly in contact. The brush-roll D is preferably located near the upper surface of cylinder C, and the stripper-roll E is located in front of the cylinder B. Above the stripper-roll is preferably located a presser of comb-like construction, 20 secured to the end walls of the hopper and provided with teeth arranged to act between the rows of teeth of the feed-cylinder and press upon the tobacco and prevent its uneven removal by the stripper-roll.
- 25 30 As shown in the drawings, the moving parts above described are connected to the prime motor and are driven as follows:
- 35 a is the main shaft, driven from pulley b, and the brush-roll D is secured to rotate with this shaft, while on its opposite end the pulley c is connected by the cross-belt d to pulley e on the shaft of the stripper-roll E, the pulley f on the opposite end of this shaft being connected by belt g to fast and loose pulley h on 40 shaft i.
- 45 The feed-cylinder B and the filling-cylinder C are driven from the shaft i through a feed-regulating device, the construction and connection of these parts being as follows:
- 50 45 The shaft i carries a cone-pulley j, which is preferably connected by the cross-belt k to a second cone-pulley l, fixed to a movable suspended shaft m, carrying a pinion n, the shaft m turning in the sleeves o on the free 55 ends of arms p, fixed to rock-shaft q, the latter being journaled in the frame of the machine. The shaft m is made laterally movable to give and maintain the desired tension on belt k to drive the cone-pulley l, and its movement is controlled by spring r, attached at one of its ends to bar s, while its other end is secured to arm t, which in turn is fixed to shaft q, the latter carrying gear-wheel u and pinion v, said pinion engaging and driving 60 gear-wheel w on shaft x, journaled in the frame of the machine, which shaft x carries a sprocket-wheel y, connected to sprocket-wheel a², arranged to rotate on stud b², by a chain belt c². Mounted on an eccentric on 65 the hub of sprocket-wheel a² is a pawl d², so arranged in relation to ratchet-wheel e², fixed to shaft f², which carries the filling-cylinder

C, that each rotation of the sprocket-wheel a² will give the free end of the pawl d², which engages the successive teeth of the ratchet-wheel, a forward thrust to intermittently rotate the cylinder C, a retaining-pawl g² being provided to prevent reverse rotation. The feeding-cylinder B is driven from a pinion h², also mounted on the hub of the sprocket-wheel a², and said pinion meshes with and drives gear-wheel i², mounted on stud k², carrying pinion j², which latter drives gear-wheel l², fixed to shaft m², on which the cylinder B is mounted. It is observed that the driving connections of the cylinders B and C with the hub of sprocket-wheel a² are such that the cylinder C is rotated intermittently, while the cylinder B is rotated continuously; also, that the speed of the surface of cylinder C when it is in motion is preferably somewhat greater than that of the cylinder B, which two conditions of operation are considered desirable.

The belt k, which connects the cone-pulleys j and l, is moved along the surface of said pulleys in order to increase or decrease the speed of shaft m and the speed of the rotation of the cylinders B and C through their connections with the shaft m by means of any device adapted for this purpose, as a screw-threaded nut n², carrying arms o², arranged to push or pull against the belt, the said nut being moved by a screw-threaded shaft p², as shown in Figs. 1 and 4.

The function of the devices thus far described is to measure from the tobacco in the hopper certain definite and determined quantities and to dispose of it in a uniform web or sheet on the surface of cylinder B and between the teeth thereof and to uniformly remove it therefrom and shower or deliver it upon a receiving-surface, for the purposes hereinafter more fully described, and the operation of these devices is, briefly, as follows:

Fibrous tobacco adapted for cigarettes, generally in an irregular, undistributed, or unarranged mass, is placed in the hopper, which by its shape causes it to rest upon the upper surface of feed-cylinder B, and as this cylinder rotates its teeth draw or comb a surplus of tobacco from the mass and carry it to the filling-cylinder and into the bite of the feeding and filling cylinders. The filling-cylinder during each of its short periods of rest from rotation forms a stationary guide which operates to press or force the fibrous tobacco down between the teeth of the feed-cylinder as the tobacco is carried forward by the continuous rotation of the latter cylinder, so as to more fully and uniformly fill the teeth than would be done were the rotation of the filling-cylinder continuous, while any undesired quantity or surplus of tobacco which has been carried forward between the cylinders is swept or forced backward toward the main mass by the quick short rotation of the filling-cylinder. The periods of rest and movement of the filling-cylinder are of very

brief duration, but are sufficient, on the one hand, to enable the teeth of the feed-cylinder to become fully filled and, on the other hand, to prevent too much surplus tobacco from passing the bite of the cylinders and the web or sheet of tobacco from being too much condensed. The result of this operation is to form the tobacco into a web or sheet of substantially uniform consistency and thickness 10 on the surface of the feed-cylinder, the thickness of the web being substantially equal to the projection of the teeth of the cylinder and its width equal to the length thereof. After the web of tobacco has been thus formed it 15 is advanced by the rotation of the feed-cylinder underneath the compressor-comb B' and thence to the stripper-roll E, whose teeth intermesh with those of the cylinder B and, co-acting with the compressor-teeth, uniformly 20 remove the tobacco therefrom and shower it down in a light fibrous condition suitable for cigarette-filters.

It is observed that as the speed of the feed-cylinder and the stripper-roll E are continuous 25 and the tobacco is continuously presented to the stripper-roll in a web of substantially uniform thickness and consistency the stripper-roll operates to remove from the feed-cylinder and shower down uniform quantities 30 of tobacco. It is also observed that the cylinder B furnishes a continuously-traveling surface provided with projecting teeth, which can be filled with tobacco to form a web or sheet of substantially uniform thickness and 35 density, and that the cylinder C provides an intermittently-traveling surface so arranged relatively to and coöperating with the surface of cylinder B as to fully and uniformly fill the teeth of the latter with the desired quantity 40 of tobacco, while the stripper-roll E operates to remove the web of tobacco from between the teeth of the traveling surface B and uniformly shower it upon any receiving-surface placed beneath it. It is not essential 45 that these traveling surfaces be cylindrical, but they may be of any suitable shape, provided they coöperate to produce the above-described results.

We will now describe the preferred form, 50 as shown in the drawings, of the mechanism or devices by which the tobacco as it is uniformly removed from the stripper-roll is received and divided into parcels upon a receiving-surface in the desired quantity and 55 shape for cigarette-filters and the devices or mechanism by which such parcels are discharged or removed from the receiving-surface and delivered to mechanism by which they are compressed to their final shape and 60 thus prepared to be associated with wrappers to form completed cigarettes.

Beneath the stripper-roll E lies an endless apron or belt G, preferably running parallel with the axis of the roll E and passing over 65 drums H H', journaled in attachments A³ A⁴, properly secured to the opposite ends of a piece I, which is fixed to the main frame of the ma-

chine. This apron is divided into a number of equal compartments by transverse partitions J, in length substantially equal to or 70 slightly longer than the length of the fillers desired and centrally secured to the body of the apron in any desired manner, but preferably, as shown in detail in Figs. 9 and 10, by screws r², countersunk in cleats s² on the underside of 75 the apron, which pass through the apron and are then screwed into the partitions J. The apron may be of leather or any suitable flexible material, and the partitions and cleats may also be of any suitable material, as wood, 80 brass, aluminium, or other metal. This compartment-apron is arranged to run between side guides a⁴ a⁵ and b⁴ b⁵, which operate to prevent the tobacco from falling out of the ends of the compartments, while the free and 85 unobstructed edges of the apron preferably run in narrow grooves c⁴ c⁵, as seen in Fig. 4.

The shape of the partitions J is preferably substantially that shown in cross-section in Fig. 10, in which the bases of the partitions are sufficiently broad to receive the clamping-screws r², while their sides converge to form thin edges, as r⁴, so that only very limited surfaces will be presented for the lodgment of fibers or particles of tobacco. A small brush-roll, as R⁴, conveniently fixed in the walls A⁴, as shown in dotted lines in Fig. 7, may be employed to remove any fibers of tobacco which may be retained upon the edges r⁴ and deposit them in the compartments. If desired, this roll may be arranged to revolve by any suitable connection to the driving mechanism. 90

Inasmuch as the discharge of the parcels of tobacco from their compartments and their delivery to mechanism for compressing them to filler form is dependent upon the movement of the compartment-apron it is important that the apron be driven in exact unison with the compressing devices, and especially that no slip of the apron on its drums be permitted. 105 For this purpose the drums H and H' are provided with longitudinal grooves K to receive the cleats s², which construction will operate substantially like a sprocket-wheel and chain belt, as seen in Figs. 1 and 7, and will make 110 the advance of the apron positive and exact. 115

In order to give the desired form to the parcels of tobacco in the apron-compartments, a deflecting-surface L is arranged above the partitions J of the apron G, the lower edge 120 of such surface or plate running in a diagonal direction relatively to the width of the apron or the length of the compartments. This deflecting surface or plate is conveniently secured to the guide a⁵, which latter is preferably made removable for the purpose of applying other deflecting-plates of different form and direction, and extends from one end of the stripper-roll E toward but preferably not entirely to the opposite end thereof, there- 125 by gradually exposing more of the width of the apron in the direction of its movement, as seen in plan in Fig. 2. 130

As the tobacco is showered down by the

- stripper-roll it is deposited in the compartments as they are advanced beneath the roll, the arrangement being such that several of the compartments receive the shower of tobacco simultaneously; but the tobacco is not distributed uniformly throughout the length of the compartments, since as it is showered down a part of the tobacco falls directly upon the exposed portion of the apron, while a part falls or is thrown upon the inclined deflecting-surface L and slides down such surface and falls from the edge thereof upon that portion of the apron or bottom of the compartments which is directly beneath such edge. As the lower edge of the deflecting-surface runs diagonally across the compartments, it results that when a series of compartments are advanced beneath the stripper-roll the tobacco will be deposited in larger quantity in the ends of the compartments which are not covered by the diagonal deflecting-surface until the compartments pass the end of such surface, when the tobacco may be deposited along the entire length of the compartments. This construction and operation will give parcels of tobacco of substantially equal quantity in each compartment; but the parcels will be larger at one of their ends and will gradually decrease in size or quantity of tobacco toward their other ends, thereby adapting them, when properly compressed, to form fillers for conical or tapered cigarettes, as shown in Fig. 12, for which this machine is more especially designed.
- A modification of the construction above described is shown in Fig. 11 of the drawings, in which a concave guide M is located beneath the stripper-roll E to cause substantially all the tobacco as it is removed from the feed-cylinder B to be carried out laterally by the stripper-teeth and thrown against the inclined deflecting-surface L instead of being showered directly down from the stripper-roll, so that a part of the tobacco will fall upon the exposed part of the apron G and a part upon the deflecting-surface L, as in the construction shown in Figs. 2 and 4, where the concave is omitted. In the modified construction substantially all the tobacco is thrown against the deflecting-surface L throughout its whole length, and as it falls or slides down such surface and drops from the edge thereof it is deposited in the compartments and upon the apron forming the bottom thereof in parcels which contain an equal or uniform quantity of tobacco throughout their length and are thereby adapted, when properly compressed, to form cigarette-filters of uniform diameter, such as are shown in Fig. 13.
- To understand more clearly the operation of the modified construction whereby the tobacco is deposited in the compartments in parcels containing equal and uniform quantities of tobacco throughout their length, it is simply necessary to consider that the concave M operates to cause substantially all of the tobacco to be thrown against the deflecting-

surface L and that it is deposited in the compartments only as it slides down such surface and drops from its edge, which edge runs diagonally above the compartments. As the compartments are advanced under and along the length of the deflecting-surface L the tobacco, as it drops from the edge of this surface, will be deposited in such part of the length of the compartments as is immediately under such edge, and for any one compartment this part will vary with the advance of the compartment by reason of the diagonal direction of the edge. So, also, as substantially equal quantities of tobacco drop from this edge in equal times, and as the advance of the compartments is uniform, it results that when any compartment has passed the entire length of the deflecting-surface L the tobacco will be deposited in a layer or parcel of substantially equal thickness throughout the length of the compartment and will be in condition when properly compressed to form a cigarette-filler of uniform diameter throughout its length.

It is desirable for the purpose of maintaining the shape of the parcels of tobacco, as well as to conform to the desired movements of the filler-compressing mechanism, to discharge each parcel from its compartment and deliver it in a single mass rather than in a shower or in dribblets, and for this reason it is preferred that the discharging devices be intermittent in their operation. It is also desired that no incomplete parcels, such as may be deposited in the compartments in starting or stopping the machine, be delivered to the compressing mechanism, and devices are shown in Figs. 1, 6, 7, and 8 for accomplishing these results. In these figures, N is as pout or chute located below the drum H and leading from the compartment-apron to the compressing mechanism, the mouth or upper opening of this spout being alternately closed and opened to each compartment by any suitable devices, as a swinging door operated by suitable mechanism. As shown in the drawings, the door O is fixed to a shaft P, journaled in the attachment A⁴, and is operated by a rotating cam R through an arm S, fixed to shaft P and held in position by spring T, attached to locking-arm U, located at the opposite end of the shaft P, as seen in Fig. 8, the cam R being fixed to sleeve V, arranged to rotate on stud W, as hereinafter more fully described.

The door O is curved, so that when in its closed position the edges of the partitions J will sweep over its interior surface and in such proximity thereto as to remove the parcels of tobacco therefrom. Between the free end of the door O or side of the spout N and the lower edge of any one of the partitions J which has passed this point, as seen in Fig. 7, is an opening X, through which the parcels can be successively raked out by the moving partitions and discharged in case they are incomplete or for any reason it is impracticable to deliver them to the compressing

mechanism, and the door O can at any time be swung into and locked in position to effect and maintain this discharge by throwing down the handle t^2 , pivoted to the attachment 5 A⁴, which will bring the part u^2 in contact with the part v^2 , which is provided with a shoulder-stop w^2 , and by thus locking the door O in position, as shown in Fig. 7, a continuous discharge of the parcels through the 10 opening X is effected.

When it is desired to bring the devices into position to discharge the parcels into the spout N, and thus deliver them to the compressing mechanism, the handle t^2 is thrown 15 backward and the door O is unlocked from its closed position and brought under the control of the cam R, as above described, and shown in Fig. 8, the rotation of the cam being so timed relatively to the movement of 20 the apron G that when the parcel of one compartment, and only one, rests on the door it will be swung open by the contraction of spring T, aided by gravity, into the position shown in dotted lines in Fig. 7, and the parcel 25 will be discharged at once or in a single body into the spout N and be delivered to the compressing mechanism.

It is important to the proper discharge of the parcels from their several compartments 30 that the side guides b^4 and b^5 opposite the ends of the drum H be cut away or provided with recesses b^6 to give clearance to the ends of the parcels, so that they will not drag on the walls of the guides or the fibers of tobacco 35 be pinched between the ends of the partitions J and the walls of the guides b^4 b^6 , it being essential that the ends of the parcels be free to fall by gravity as the apron passes around the drum.

40 It is preferred that the chute N, through which the parcels fall as they pass from the discharging mechanism to the compressing mechanism, be slightly narrower at its lower than at its upper end, in order that the tobacco 45 at the ends of the parcels may be "evened up" and somewhat concentrated, so that the ends of the completed cigarettes will be well filled, which is important. This is easily effected by making the edge walls of 50 the chute to gradually and slightly converge toward the bottom of the chute, as shown in dotted lines in Fig. 6.

The filler-compressing mechanism may be 55 of any construction and operation adapted to receive the parcels of tobacco and compress them to the desired extent for cigarette-filters. In Fig. 1, at the left hand and near the bottom thereof, is shown a part of a mechanism for this purpose, the same being more 60 fully described and shown in United States Letters Patent No. 565,852, dated August 11, 1896. The mechanism as shown in Fig. 1 consists generally of a series of molds a^3 , mounted in a holder b^3 , arranged on shaft c^3 65 to rotate horizontally and intermittently, the molds being composed of two main parts—a stationary part d^3 and a sliding part e^3 —and

means for operating the latter to open and close the molds to receive and compress the tobacco to filler form; also, of a surface or 70 hopper f^3 for receiving the parcels of tobacco, a pusher or plunger g^3 to bring the parcels underneath the open mold, and a vertically-moving plunger h^3 to push the parcels up between the face of the pusher g^3 and a guide 75 i^3 and into the molds, and means for actuating these devices at the proper times relatively to the movements of the molds, the pusher g^3 being operated by the cam-face of the wheel j^3 through roller k^3 and the plunger h^3 by a vertical slide m^3 , operated by a roller running in a groove in the opposite face of wheel j^3 . These parts, as stated, are fully described in the specification and shown in the drawings of said patent, No. 565,852. 85

It is not considered essential to provide a spout or chute, as N, to connect the parcel-discharging mechanism with the filler-compressing mechanism, since the parcels can be discharged directly through the open door 90 O to the hopper f^3 of the compressing mechanism.

As hereinbefore stated, it is essential that the parcel discharging and delivering mechanism be driven in exact unison with the compressing mechanism, so that the successive parcels of tobacco shall always be delivered to the latter mechanism at such times as the devices thereof are in position to receive and operate upon them in their proper order of 95 succession. To effect this, the drum H, which drives the compartment-apron G, is driven through positive and exact operating connections from the shaft A², which drives the compressing mechanism, these connections, as 100 shown in the drawings, being as follows: Counter-shaft n^3 , journaled to the frame of the machine, is driven by beveled gear-wheel o^3 , meshing with a corresponding bevel gear-wheel p^3 on shaft A², the counter-shaft carrying a sprocket-wheel q^3 , connected to and driving by chain belt r^3 a sprocket-wheel s^3 , fixed to sleeve V, rotating on stud W and carrying pinion v^3 and cam R, the pinion v^3 meshing with and driving gear-wheel u^3 , affixed to the 110 shaft of the drum H, which, as before described, drives the compartment-apron G.

As shown in the drawings, the compressing mechanism is driven from shaft i , which carries the coned pulley j , through the gear-wheels x^3 and y^3 , the latter being fixed to shaft A², thus driving the compressing mechanism from the prime motor of the tobacco measuring and distributing mechanism; but instead of this connection the compressing 125 mechanism may be driven from a separate motor, provided the compartment-apron G be driven from the same motor.

We do not desire to limit our invention, so far as it relates to the intermittent movement 130 of the filling-cylinder C in connection with the feed-cylinder B, to the special construction of these cylinders or to the special connections for driving them herein described

and shown in the drawings, as these can be varied without affecting the principle of its construction and operation; nor do we wish to limit our invention to the special construction and operation of the series of compartments for receiving the parcels of tobacco for cigarette-filters, or to the special means for depositing the proper quantity of tobacco in such compartments, or for discharging the same therefrom, or to the special means for connecting the discharging mechanism with the compressing mechanism shown in the drawings, as all these constructions can be varied without departing from the principle 15 of the invention.

What is claimed as new is—

1. In cigarette machinery, the combination substantially as set forth, of a continuously-traveling feeding-surface provided with teeth and an intermittently-traveling filling-surface, the said feeding and filling surfaces being arranged so that their contiguous surfaces will travel in opposite directions, for the purpose set forth.
2. In cigarette machinery, the combination substantially as set forth, of a continuously-traveling feeding-surface provided with teeth and an intermittently-traveling filling-surface, the said filling and feeding surfaces being arranged so that their contiguous surfaces will travel in opposite directions and the speed of the filling-surface when in movement will be greater than that of the feeding-surface, for the purposes set forth.
3. In cigarette machinery, the combination substantially as set forth, of a continuously-rotating feed-cylinder provided with teeth and an intermittently-rotating filling-cylinder, the cylinders being arranged so that their contiguous surfaces will rotate in opposite directions, for the purpose set forth.
4. In cigarette machinery, the combination substantially as set forth, of a continuously-rotating feed-cylinder provided with teeth and an intermittently-rotating filling-cylinder, the cylinders being arranged so that their contiguous surfaces will rotate in opposite directions and the peripheral rotative speed of the filling-cylinder will be greater than that of the feeding-cylinder, for the purposes set forth.
5. In cigarette machinery, a series of advancing compartments adapted to contain parcels of tobacco of shape and size for forming the cigarette-filters desired, in combination with means for simultaneously delivering to several of the compartments the desired quantity of tobacco and disposing the same therein in the desired shape for the parcels, and means for discharging the parcels from compartments.
6. In cigarette machinery, the combination substantially as set forth, of a series of advancing compartments adapted to contain parcels of tobacco for cigarette-filters, means for simultaneously delivering tobacco to several of the compartments and disposing it in

larger quantity at one end of the compartments and gradually decreasing toward the other end, and thereby forming parcels of tobacco of shape and size adapted upon compression to form conical or tapered cigarette-filters.

7. In cigarette machinery, the combination substantially as set forth, of an endless apron divided by transverse partitions into compartments of substantially the length of the cigarette-filters desired, mechanism for showering tobacco into such compartments in quantity and disposition to form parcels for cigarette-filters and means for discharging the parcels from the compartments.

8. In cigarette machinery, in combination with an endless apron divided by transverse partitions into a series of compartments adapted to contain parcels of tobacco in shape and size for cigarette-filters, mechanism for showering tobacco into the compartments, means for advancing such compartments and means for discharging the contents therefrom, of side guides to retain the tobacco in the compartments.

9. In cigarette machinery, in combination with an endless apron divided by transverse partitions into a series of compartments adapted to contain parcels of tobacco in shape and size for cigarette-filters, means for advancing such compartments and means for discharging the contents therefrom, of side guides to retain the tobacco in the compartments, said side guides being cut away or at a greater distance apart at or near the place of discharge to give the desired clearance to the parcels, substantially as described.

10. In cigarette machinery, the combination of a series of compartments adapted to contain parcels of tobacco for cigarette-filters, means for showering tobacco, a deflecting-surface arranged diagonally above the compartments operating to deliver the showered tobacco in larger quantities to one end of the compartments than to the other and means for advancing the compartments, whereby the parcels formed therein are adapted for conical or tapered cigarette-filters.

11. In cigarette machinery, the combination of an endless apron carrying a series of compartments adapted to contain parcels of tobacco for cigarette-filters, means for advancing the apron, means for showering tobacco and a deflecting-surface arranged diagonally above the compartments and operating to deliver the showered tobacco in larger quantities to one end of the compartments than to the other, whereby the parcels are adapted for conical or tapered cigarette-filters.

12. In cigarette machinery, the combination substantially as set forth, of mechanism for showering tobacco, a series of moving compartments for receiving the showered tobacco, a deflecting surface or plate arranged diagonally between the showering mechanism and the compartments and means for direct-

ing the entire shower of tobacco upon the said deflecting-surface substantially throughout its entire length, whereby the showered tobacco will be thrown upon the deflecting-plate and will be delivered therefrom into the compartments to form parcels adapted for cigarette-filters of uniform diameter.

13. The combination of a stripper-roll, as E, a concave guide, as M, arranged beneath the stripper-roll, a series of compartments adapted to contain parcels of tobacco for cigarette-filters, means for advancing the same and a deflecting-surface, as L, arranged above and diagonally of the compartments, whereby the tobacco will be delivered from the stripper-roll to the diagonal deflecting-surface and thence to the compartments to form parcels adapted for cigarette-filters of uniform diameter.

20 14. The combination, in an endless apron divided into compartments, of transverse partitions, as J, located on one side of the apron, cleats, as s^2 , located on the other side of the apron and opposite the base of the partitions and screws, as r^2 , passing through the cleats and apron and into the base of the partitions, substantially as set forth.

15. In cigarette machinery, the combination substantially as set forth, with a series 30 of moving compartments for containing parcels of tobacco for cigarette-filters, of a door, as O, means for bringing the parcels of each compartment successively to rest upon the door when in its closed position, means for 35 opening the door to discharge each parcel as it is brought to rest upon it and mechanism for closing the door before the next succeeding parcel is brought into discharging position.

40 16. In cigarette machinery, the combina-

tion substantially as set forth, with a series of moving compartments adapted to contain parcels of tobacco for cigarette-filters, mechanism for compressing the parcels to filler shape, mechanism for discharging the complete parcels from the compartments and delivering them to the compressing mechanism and mechanism for discharging the incomplete parcels whereby they will not be delivered to the compressing mechanism.

45 17. In cigarette machinery, the combination substantially as set forth, with a series of moving compartments for containing parcels of tobacco for cigarette-filters and mechanism for compressing the parcels to filler shape, of a door, as O, through which the complete parcels are delivered to the compressing mechanism, devices for retaining the door closed to the compressing mechanism for an 50 indefinite period to permit the partitions of the compartments to carry incomplete parcels over the free end of the door and discharge them outside of the compressing mechanism.

55 18. The combination with a series of compartments for containing parcels of tobacco and a drum, as H, around which the compartments are advanced, of a door, as O, so curved in its closed position that the ends of the compartment-partitions will sweep over its interior surface and discharge the incomplete parcels over the free end of the door while in its closed position, substantially as 60 and for the purpose set forth.

65 JAMES A. BONSACK.
HUGO BILGRAM.
